(57) **CLAIM**

The ornamental design for a “portion of container,” as shown and described.

DESCRIPTION

FIG. 1 is a perspective view showing my new design; FIG. 2 is a side elevational view, the opposite side elevational view being identical; and,

FIG. 3 is a front elevational view, the rear elevational view being identical.

The broken lines shown in the drawings are for illustrative purposes only and form no part of the claimed design.
